UNITED STATES PATENT OFFICE.

EMIL THEODORE PALMENBERG, OF NEW YORK, N. Y.

DESIGN FOR A PEDESTAL FOR MERCHANDISE DISPLAY FIXTURES.

Application filed March 16, 1925. Serial No. 12,737. Term of patent 7 years.

To all whom it may concern:

Be it known that I, EMIL T. PALMENBERG, a citizen of the United States, and a resident of the city of New York, borough of Manhattan, in the county and State of New York, have invented a new, original, and ornamental Design for a Pedestal for Merchandise Display Fixtures, of which the following is a specification, reference being had to the accompanying drawing, forming part thereof.

The drawing is a perspective view of a pedestal for merchandise display fixtures, showing my new design.

I claim:—

The ornamental design for a pedestal for merchandise display fixtures.

EMIL THEODORE PALMENBERG.
